COMBINED MAGNIFYING GLASS AND MEMORANDUM PAD

Murray A. Levin, New Haven, Conn.

Application January 16, 1956, Serial No. 39,763

Term of patent 3½ years

(Cl. D74—1)

Fig. 1.

Fig. 4.

Fig. 2.

Fig. 1 is a top plan view of a combined magnifying glass and memorandum pad, showing my new design.

Fig. 2 is a bottom plan view thereof.

Fig. 3 is a top edge view thereof; and

Fig. 4 is a side view thereof, as viewed from the right of Fig. 1.

I claim:

The ornamental design for a combined magnifying glass and memorandum pad, substantially as shown.
